UNITED STATES PATENT OFFICE.

CARL OLAF ANDERSEN DÖVLE, OF NOTODDEN, NORWAY, ASSIGNOR TO NORSK HYDRO-ELEKTRISK KVAELSTOFAKTIESELSKAB, OF CHRISTIANIA, NORWAY.

ELECTRIC-ARC FURNACE FOR THE TREATMENT OF GASES.

1,194,606.

Specification of Letters Patent. Patented Aug. 15, 1916.

Application filed May 10, 1915. Serial No. 27,116.

To all whom it may concern:

Be it known that I, CARL OLAF ANDERSEN DÖVLE, a subject of the King of Norway, residing at Notodden, Norway, have invented certain new and useful Improvements in Electric-Arc Furnaces for the Treatment of Gases; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the electric arc furnaces which are used for instance in the oxidation of nitrogen and in which the electric arc is spread magnetically to a flame disk, the air or gases usually are so conducted through the furnace that they pass as closely as possible along the whole flame surface. The gases either are introduced through holes directed toward the flame disk and taken out at the periphery, or they are introduced at the periphery and taken out near the central part of the furnace. In some cases it has however been found to be of advantage, when the gases are made to pass over only part of the flame disk during their passage through the furnace. In particular this is the case where no special means are provided for regulating the flow of gases. In a furnace of the well known Birkeland-Eyde type it has been found that a considerably better reaction and cooling effect may be attained by disposing the outlet openings systematically instead of taking out the gases as usual through openings at the periphery. It has also been found, that the diameter of the furnace may be reduced considerably in this way.

According to the present invention a number of outlet openings of suitable form and cross section are disposed between the center and the periphery of the furnace, while the air or gas inlets may be disposed as usual in relation to the flame disk. In this way there is created a number of fields, varying according to the capacity of the furnace, and in which the air or gases are being conducted along paths, which are considerably shorter than in an ordinary furnace. This will be best understood by reference to the drawings, which illustrates diagrammatically the

application of the invention on a Birkeland-Eyde furnace.

A is the furnace. The flame disk inside the same is indicated by the dotted line B. C are the air inlets, which are disposed as usual in a large number over the substantial area of the flame disk B.

The outlet openings are indicated by D, a number of such openings being disposed between the center and the periphery of the furnace so as to form separate fields of flowing gas or air, the gas or air paths in said fields being considerably shorter than the gas or air paths in an ordinary furnace. The gas or air paths in the furnace may also be regulated by providing inlet openings, which form an angle with the flame disk. Further the capacity of the different outlets may be regulated, thereby influencing the length of the gas or air paths, until the best possible heating and cooling conditions are obtained.

The increased output of the furnace according to the present invention possibly also is due to the effective cooling caused by part of the cold gases being sucked out through the comparatively narrow outlets together with the heated gases. This effect may be increased by providing the outlets with cooling devices E, for instance, as indicated, in the form of a cooling tube. The outlets may also be provided with devices (not shown) for imparting to the gases a turbulent movement around a cooling device.

Claims:

1. In an electric arc furnace for the treatment of gases a magnetically spread flame disk, gas inlet openings for introducing the gas into the furnace disposed over the area of the flame disk, and a number of gas outlets disposed between the center and the periphery of the said furnace with the object of obtaining a short passage of gases in the furnace.

2. In an electric arc furnace for the reduction of gases a magnetically spread flame disk, gas inlet openings for introducing gas into the furnace, said openings being disposed angularly to the flame disk and over the substantial area of the same and a number of gas outlets disposed between the center and the periphery of the said furnace with the object of obtaining a short passage of gases in the furnace.

3. In an electric arc furnace for the re-

duction of gases a magnetically spread flame disk, gas inlet openings for introducing gas into the furnace, disposed over the area of the flame disk, and gas outlets located between the center and the periphery of the furnace, said outlets being provided with means for cooling the gases with the object of obtaining short gas passages in the furnace and an effective cooling of the gases after leaving the furnace chamber.

4. An electric arc furnace producing a magnetically spread flame disk having inlet openings in its side walls for the admission of gas through its sides to said flame disk and outlet openings disposed between the center of said disk and its periphery, whereby gas treated by said arc will exit through said outlet openings at points intermediate the ends of the radii of said disk.

5. An electric arc furnace producing a magnetically spread flame disk having outlet openings in its side walls between the center

of said disk and its periphery surrounded by a number of inlet openings.

6. An electric arc furnace producing a magnetically spread flame disk having outlet openings in its side walls disposed between the center of said disk and its periphery and surrounded by a number of smaller inlet openings whereby gases will be subjected to the action of said arc disk in fields eccentric thereto.

7. An electric arc furnace for producing a magnetically spread flame disk having inlet openings in its side walls disposed over the area of said disk, and outlet openings disposed between said inlet openings at points between the center and periphery of said disk, and cooling means arranged in the paths of the gases issuing from said outlet openings around which the treated gases flow.

In testimony that I claim the foregoing as my invention, I have signed my name in presence of two subscribing witnesses.

CARL OLAF ANDERSEN DØYLE.
